UNITED STATES PATENT OFFICE

FRED M. TIES, OF BRODHEAD, WISCONSIN

ROD AND PIPE GRAPPLE

Application filed August 15, 1931. Serial No. 557,363.

This invention relates to grappling devices and pertains particularly to a device designed for catching rods in wells or sewers, which may have become broken or disjointed while working in the well or cleaning out the sewer.

The primary object of the present invention is to provide a device which may be readily inserted into a sewer or into a well hole, and which will easily pass over the end of a broken rod therein but when moved in the reverse direction will grip the rod so that it may be easily removed.

Another object of the invention is to provide a device which may be readily extended into a sewer even though the same may be clogged with roots or other material, the device being so formed as to cut its way through the clogging matter.

A still further object of the invention is to provide a device of the above described character which is so designed that the rod or pipe engaged thereby may be released if it is found to be lodged in such a manner that its removal cannot be effected.

The invention will be best understood from a consideration of the following detailed description taken in connection with the accompanying drawing forming part of this specification, with the understanding, however, that the invention is not confined to any strict conformity with the showing of the drawing but may be changed or modified so long as such changes or modifications mark no material departure from the salient features of the invention as expressed in the appended claims.

In the drawing:

Figure 1 is a view in side elevation of the rod and pipe grapple embodying the present invention.

Figure 2 is a view in elevation looking toward the head of the device.

Figure 3 is a sectional view taken on the line 3—3 of Figure 2.

Referring more particularly to the drawing, wherein like numerals of reference indicate corresponding parts throughout the several views, the numeral 1 indicates the forward end or head portion of the device embodying the present invention which, as

shown, is of cylindrical design and is open at each end. This head or cylinder 1 is formed of tempered steel and has its forward edge sharpened, as indicated at 2, so that it may be easily driven through roots or other obstructions with which it may come into contact while it is in use.

The head 1 is connected with a rod 3 by a plurality of arms, each of which is indicated by the numeral 4. These arms, which are preferably four in number, are secured to the rear edge of the head and extend a substantial distance therefrom parallel to the axial center thereof and then bend inwardly in convergent relation, as indicated at 5, and have their inner ends extended along the sides of the rod 3, as indicated at 6. Securing bolts or rivets 7 are passed through the inner ends of the arms and through the carrying rod 3 to secure the arms in position thereon and also to secure the rod to extend substantially axially of the cylindrical head.

Within the head 1 there is positioned a plate 8 which is mounted for oscillation upon a bar 9 which has its ends secured in the wall of the head. Any suitable means may be employed for attaching the plate 8 to the rod 9, the means here illustrated consisting of loops or ears 10 formed integral with the edges of the plate and having the bar 9 extended therethrough.

The edge of the plate 8 opposite that edge which is attached to the bar 9 is cut inwardly and provided with teeth 11, this incut edge forming with the adjacent wall portion of the head a substantially elliptical opening in which a rod or pipe engaged by the device positions.

Adjacent the toothed edge portion 11 of the plate 8 there is attached at 12 one end of a chain 13 which passes rearwardly through a guide eye 14 carried by the arm 4 which will be located at the top of the head when the device is in use.

From this eye 14 the chain 13 passes to and through a second eye 15 which is mounted upon the rod 3 where it terminates in a loop 16 to which is attached one end of a rope or cable 17.

The rod 3 has attached to the end, oppo-

- site that end to which the head is connected, a joint unit 18 of the character commonly employed for coupling together rods used for running clean-out devices through sewer or other pipes, so that the necessary additional rods may be connected with the rod 3 to facilitate the introduction of the head 1 into the pipe or passage in which is located the rod or pipe section to be recovered.
- 10 From the foregoing description it will be readily understood that in the use of the present grapple the head 1 is run into the sewer pipe or well hole and when it reaches the point where the broken pipe or rod is located, it will run over the end of the latter which will push the plate 8 rearwardly and find its way between the toothed edge of the plate and the wall of the head. Upon reversing the movement of the head the plate 8 will swing down and bind the engaged pipe or rod against the wall of the head, so that the rod may be then drawn out. Should it be found that the engaged rod or pipe is so fixed that it cannot be moved, the operator of the grapple may release it by pulling upon the cable 17 so as to swing the plate free from engagement therewith.
- 15 It will also be readily seen that the device herein set forth may be easily and inexpensively manufactured and operated successfully for engaging broken pipe in wells or broken rods in sewer pipes, so that their removal may be effected.
- 20 At the rear end of the rod 3, there is secured thereto by means of a bolt 19 which is passed through the forward end portion 6 of two of the members 4, a clevis 20. This clevis is provided so that a chain or cable may be coupled with the device for the connection of a power mechanism thereto such as a motor vehicle or the like, where a heavy or tightly engaged body is gripped by the device which cannot be removed by pulling on the rod 3 by hand.
- 25 Having thus described the invention, what is claimed is:

1. A grapple device of the character described, comprising a short cylindrical body having the edge at one end sharpened, a rod member connected with the other end of the body and extending axially thereof, a plate member disposed transversely of and within the body, pivotal supporting means for said plate permitting its oscillation longitudinally thereof and a flexible member connected with said plate to facilitate the movement of the plate from a point remote therefrom.
2. A grapple of the character described, comprising a short cylindrical body, a plurality of arms extending from one end of the body and longitudinally thereof, a rod member having one end disposed between the ends of the arms remote from the cylinder body and secured thereto, a plate member disposed transversely of and within the cylinder body

and mounted for oscillation longitudinally therein, said plate having a portion of the edge cut out and formed to provide teeth therealong, and a flexible element connected at one end with said plate and extending rearwardly thereof along said rod to facilitate the actuation of the plate from a remote point.

3. A grapple of the character described, comprising a short cylindrical body, a plurality of arms extending from one end of the body and longitudinally thereof, a rod member having one end disposed between the ends of the arms remote from the cylinder body and secured thereto, a plate member disposed transversely of and within the cylinder body and mounted for oscillation longitudinally therein, and a clevis mounted upon said rod for the connection of a pull device therewith.

4. A grapple device of the character described, comprising a tubular body, a plurality of arms extending from one end of the body and having their free ends in convergent spaced relation, a rigid bar member secured at one end between the convergent ends of said arms, a plate member oscillatably mounted within the tubular body upon a transverse axis and having an edge formed to frictionally bind against a body extended through the tubular body, a flexible pull member connected at one end to said plate and extending longitudinally of said bar, and guides mounted upon one of said arms and said bar through which said flexible member is extended.

5. A grapple of the character described, comprising a cylindrical body, a plurality of arms extending from one end of said body and having portions of their free ends in spaced convergent relation, a plate member mounted within the tubular body upon an axis extending transversely thereof and having an edge formed to frictionally engage an elongated member extending through the tubular body, an elongated flexible member connected at one end with said plate, a rigid bar member connected at one end between the convergent ends of said arms, and a coupling member upon the other end of said rigid bar member for facilitating the connection of another bar therewith.

In testimony whereof I hereunto affix my signature.

FRED M. TIES.
